UNITED STATES PATENT OFFICE.

ANDREW J. WILEY, OF BOISE, IDAHO.

METAL BASE FOR TIMBER POLES.

Application filed January 4, 1927. Serial No. 158,960.

This invention relates to protecting and supporting bases or repair elements for poles carrying electric transmission wires.

Telephone, telegraph, and electric transmission wires are usually carried on round poles set in holes in the ground. These poles are subject to rapid decay because of their being kept in a semi-moist condition by their contact with the soil. This decay occurs from 1 to 2 feet below the ground line, the pole both above and below this zone of decay being reasonably durable, and repairs are usually made either by building a reinforced concrete base around the pole to span the decayed portion or more commonly by wiring or bolting the pole to a timber post or "stub" set deep into the ground at the base of the pole. The concrete base is very expensive and the timber stub repair, though less expensive, is still relatively quite expensive, is not durable and is objectionable on account of its awkward and unworkmanlike appearance. There are many millions of these poles and in addition to the great economic loss due to their rapid decay, their frequently recurring replacement is a severe drain on the country's timber resources.

An object of the invention is the provision of a device which will furnish a cheap and permanent repair to telephone, telegraph, and electric transmission lines in need of repairs or replacement caused by the decay at the base of the poles and which will also furnish a cheap and substantially permanent base for new poles.

Another object of the invention is the provision of a device for not only preventing decay of the bases of new telephone and telegraph poles by maintaining the timber part of the poles above ground but for protecting both new and old poles against destruction from grass and brush fires by a metal covering of slightly appearance which extends above the ground a sufficient distance for the purpose.

A further object of the invention is the provision of supporting and protecting metal coverings for electric transmission line poles which may be readily driven into position thus eliminating the cases of the usual unsightly and expensive concrete bases employed in supporting and protecting the decayed bases of poles.

This invention will be best understood

from a consideration of the following detailed description in view of the accompanying drawings forming a part of the specification nevertheless it is to be understood that the invention is not confined to the disclosures being susceptible of such changes and modifications which shall define no material departure from the salient features of the invention as explained in the appended claims:

Figure 1 is a horizontal section of my device shown applied to a pole,

Figure 2 is a fragmentary view in perspective of my device disclosing the method of locking sections of the covering together,

Figure 3 is a view in elevation of my device showing the method of application,

Figure 4 is a view in elevation of my device showing position of the sections of my device during positioning and assembling, and

Figure 5 is a view in elevation of my device disclosing the final position of the sections in embracing relation with a pole.

The invention consists of a cylindrical metal sleeve which is fitted tightly around the sound part of the pole above the ground and extended a sufficient distance into the ground to give proper support. In the case of an old pole, the sleeve also fits tightly around the sound part of the pole and below the decayed part. In the case of a new pole, the sleeve is fitted tightly around the base of the pole which is kept above the ground line, and the cylindrical sleeve is extended the proper distance into the ground to give the necessary support.

The sleeve consists of a metal tube or cylinder of circular contour made in two or more sections 10 and 11 by splitting on a plane passing through its longitudinal center line. The sleeves are made of corrugated metal rolled or pressed to form a portion of a cylinder of approximately the same diameter as the pole it is intended to fit and with the corrugations 12 parallel to the center of the cylinder. The parts of the sleeve may either be made in halves with two forming a complete cylinder or they may be made in any number desired, with each part rolled to the diameter of the completed cylinder.

The edges 13 of the rolled sheets are connected by a locking device consisting of a T section or lock frame 14 of the same length

- as the sleeve with 2 L sections or lock bars of the same length. Each wing 16 of the top of the T is formed to fit the inside of one of the corrugations 12 of the sleeve, and one leg 17 of each L is formed to fit the outside of one of these corrugations, while the other leg 18 of the L is made to fit the straight leg 19 of the T. The sections of the sleeve are connected by inserting the lock bar 15 from 10 one end lengthwise into the recess formed between the straight leg and the corrugated wing 18 of the lock frame 15 while the corrugations of the adjacent edges of the parts forming the cylinder are engaged with the corrugations of the lock frame, thus locking the parts of the sleeves to the lock frame and through the frame, to each other, but permitting longitudinal motion of the sections with respect to the lock joint or each other.
- 10 In applying the device to an old pole already in the ground, two or more sections are selected of such size that when secured together by the lock joint, the completed sleeve will fit tightly around the pole. The sections are held against the pole with the lock frames in place engaging with the corrugations of the sleeve. The lock bars are then inserted in the top of the lock frame as shown in Fig. 3. They are then driven down as shown in Fig. 4, with their ends flush with the top and bottom of the sleeve. The sleeve is then either driven or "jacked" down around the base of the pole 20 to the proper position as shown in Fig. 5, with the tops 21 of the sections 10 and 11 projecting above the ground.
- 15 In this position, if the sleeve has been properly fitted, the corrugations will be slightly stretched and somewhat bedded in the pole due to the forcing of the tightly fitting sleeve down over the increasing diameter of the tapered pole. This will provide an elastic element to take care of the expansion and contraction of the sleeve from temperature and of the pole from moisture.
- 20 In using the device in connection with new poles, one or more sections of the sleeve, forming together not more than half a complete sleeve, are driven a short distance into the ground. The pole is then erected and held against the driven sections of the sleeve. The remaining sections of the sleeve are then placed around the pole and secured to the driven part by the lock joints. The 25 newly placed sections are then driven to the same position as the first driven sections, and the operation is completed by successive alternate driving of the sections of the sleeve to their proper depth.
- 30 The substitution of the driving of metal sections for the ordinary process of digging deep holes and refilling them is a great saving in labor, especially in wet or caving ground.
- 35 The metal base is neat and attractive in

appearance as compared with the repairing of old poles by any other method and especially by the usual process of "stubbing."

The cost of the metal base in place is less than the cost of the extra length of a new pole without the metal base and the labor of digging and setting, and is less than the cost of the labor and material for concrete bases or for "stubbing" on old poles.

The metal base can be protected by galvanizing or other suitable coating to give it a very long life as compared with new poles set in the ordinary way, or with the repairs of old poles by any except the very expensive method of setting them in concrete bases.

What I claim as my invention and seek to secure by patent is set forth as follows:

1. In a metal base for fixing timber poles in the ground a cylindrical metal sleeve divided into a plurality of sections by planes parallel to its axis, the said sections of the sleeve being firmly joined together in a circumferential direction but having free movement parallel to the axis of the cylinder along a joint made of a combination of a T shaped bar with two L shaped bars which together form the joint, the top of the T being corrugated to fit interiorly with the corrugations of the sleeves, the leg of the T passing between the parallel edges of the sections of the sleeve and having a cross at its exterior and bearing against the exterior ends of the legs of the two L bars, one leg of each of which is corrugated to fit the exterior corrugation of the sleeve, and the locking being effected by the clamping of the corrugations of the sleeves between the conforming corrugations of the interior T bars and the exterior L bars.

2. A base for fixing timber poles in the ground comprising a metal sleeve formed of a plurality of sections corrugated lengthwise, and means for locking the adjacent edges of the section together, said locking means including a T rod having corrugated flanges engaging the corrugations of the sections and lock bars for wedging the T bar to the edges of the section.

3. A base for fixing timber poles in the ground comprising a metal sleeve formed of a plurality of sections corrugated lengthwise, and means for locking the adjacent edges of the section together, said locking means including a T rod having corrugated flanges engaging the corrugations of the sections and lock bars having corrugated flanges or wings engaging the corrugated portions of the sections, said bars adapted to wedge the T bars to the sections.

4. A base for fixing timber poles in the ground comprising a metal sleeve formed of a plurality of sections corrugated lengthwise, and means for locking the adjacent edges of the section together, said locking means including a T rod having corrugated

flanges engaging the corrugations of the sections and lock bars of L shape construction having straight portions engaging the T bars and corrugated wings or flanges seated 5 on the corrugated sections.

5. A metal base for fixing timber poles to the ground comprising a cylindrical metal sleeve with longitudinal corrugations divided into a plurality of sections by splitting along the lines of the corrugations, the 10 said sections being firmly joined together circumferentially but capable of being driven past each other longitudinally along a joint comprising a T shaped bar with two 15 L shaped bars which together form the joint, the top of the T being corrugated to fit interiorly with the regular corrugations of the sleeves, the leg of the T passing between opposite faces of the sections of the sleeve 20 and having a cross at its exterior end bearing against the exterior ends of the legs of the two L bars, one leg of each of which is corrugated to fit the exterior corrugation of the sleeve, and the locking being effected by 25 the clamping of the regular corrugations of the sleeve between the conforming corrugations of the interior T bars and the exterior L bars.
6. In a metal base for fixing timber poles 30 to the ground a longitudinally corrugated cylindrical metal sleeve formed of a plurality of sections connected by joints, each joint comprising a T shaped and two L shaped members having corrugated portions and

clamping the regular corrugations of the 35 sections between conforming corrugated portions of the T and L shaped members firmly together circumferentially but capable of being driven longitudinally past each other along a joint, the said cylindrical metal sleeve being made to elastically embrace the timber pole above the ground line and being driven far enough into the ground to give proper support to the pole.

7. In a metal base for timber poles, a longitudinally corrugated cylindrical metal sleeve made in a plurality of sections connected together, means for connecting the sections together and comprising a continuous T-shaped member, and continuous L-shaped members interlocked with the T-shaped member and clamping the adjacent edges of the several sections to the sleeve and to the T-shaped member, thereby forming a 50 snug rigid cylinder of equal strength at the joint both in tension and compression, as in the body of the sleeve.

8. In a metal base member for timber poles, a cylindrical metal sleeve made in a plurality of sections, joints connecting the 60 sections together and consisting of a T-shaped member and L-shaped members interlocked with the T-shaped members, and clamping the adjacent edges of the sections of the sleeve to the T-shaped member while 65 permitting the driving of an individual section into the ground around the pole.

ANDREW J. WILEY.
